UNITED STATES PATENT OFFICE.

CHARLES MATTHIEU EDELHAUSEN, OF LONG ISLAND CITY, NEW YORK.

HELMET.

1,154,494.

Specification of Letters Patent. Patented Sept. 21, 1915.

Application filed July 3, 1914. Serial No. 848,831.

To all whom it may concern:

Be it known that I, CHARLES M. EDELHAUSEN, a subject of the Emperor of Germany, residing at Astoria, Long Island City, 5 in the county of Queens and State of New York, have invented certain new and useful Improvements in Helmets; and I do hereby declare the following to be a full, clear, and exact description of the invention, such as 10 will enable others skilled in the art to which it appertains to make and use the same.

This invention comprehends certain new and useful improvements in helmets and has for its primary object to provide a device 15 of this character which will be of improved and simplified construction and which will be formed in such manner that a supply of air may be stored between the inner and outer helmet sections to be fed to the party 20 using the helmet to permit said party to travel through an inclosure filled with smoke or strong acid fumes without danger of the smoke or fumes passing into the mouth and nostrils of the person.

25 The invention has for another object to provide a helmet of this character which will be constructed in such manner that it will readily adjust itself to the head and upper portion of the body of the person to 30 whom it is applied and will be of such form as to prevent the surrounding atmosphere from reaching the head of said person.

The invention has for a further object to 35 provide a device of this character which will be of such construction that the stored air between the inner and outer sections of the helmet may be readily fed to the mouth and nostrils of the party using the helmet and the passage of said air to the mouth and 40 nostrils of the person readily regulated, as desired.

The invention has for a still further object to 45 provide a device of this character which will be constructed in such manner that the air, after being inhaled and exhaled by the party using the helmet, may find a ready escape from the helmet without danger of mixing with the fresh pure air being fed to the mouth and nostrils of the party.

50 With these and other objects in view as will become more apparent as the description proceeds, the invention consists in certain novel features of construction, combination and arrangement of parts as will be 55 hereinafter more fully described and claimed.

For a complete understanding of my invention, reference is to be had to the following description and accompanying drawings, in which—

60 Figure 1 is a front elevation of the complete device, Fig. 2 is an enlarged vertical sectional view on the plane of line 2—2 of Fig. 1, Fig. 3 is a vertical sectional view on the plane of line 3—3 of Fig. 2, Fig. 4 is 65 a fragmentary top plan view, and Fig. 5 is an enlarged detail sectional view on the plane of line 5—5 of Fig. 3, showing the construction of the inlet valve in the filling opening.

70 Referring in detail to the drawings by numerals, 1 designates the inner wall and 2 the outer wall of the upper dome-shaped construction of helmet, and it will be understood that the walls 1 and 2 are formed of 75 metal or other suitable material and are suitably reinforced by a pair of curved reinforcing plates 3 positioned between the same and slightly inclined, said plates 3 meeting at the front and back of the dome 80 and having suitable openings 4 to form communication between the upper central chamber 5 of the helmet and the second chamber 6 extending around the lower portion of the upper dome-shaped section of 85 said helmet. It will also be understood that the lower edge of the dome-shaped section of the helmet is closed by extending the lower edge 7 of the inner wall 1 outwardly and securing the same to the corresponding 90 edge of the outer wall 2.

When the helmet is in position upon a person's head, the inner wall 1 of the upper dome-shaped section of the helmet rests upon the person's head and the helmet is retained 95 in proper spaced relation with respect to the party's face, by means of a spacing strip 8 formed of rubber or other suitable material and secured to the inner face of the wall 1 at the front thereof and directed inwardly for engagement against the person's forehead, as will be clearly understood by referring to Fig. 2 of the drawings. The inner wall 1 and outer wall 2 of the upper dome-shaped section of the helmet are also 105 provided with registering spaced openings 9 within which suitable transparent members 10 are positioned to serve as lenses or sight members, it being understood that said members 10 are opposite the person's eyes 110 when the helmet is in proper position. I have also provided a pair of sleeves 11 be-

tween the inner wall 1 and outer wall 2, extending from the flanges in the wall 1 to the flanges in the wall 2, to protect said lenses 10 and further serves to reinforce the upper dome section of said helmet. It will also be evident that the sleeves 11 will serve as sight tubes.

Secured in the upper portion of the outer plate 2 of the upper dome-shaped section of the helmet is a valve tube 12 which has a valve opening 13 in its lower end, while a cap 14 is removably positioned upon the upper or outer end of said tube 12.

The tube 12 is secured in the opening 15 formed in said wall 2 by being threaded through the closure ring 16 secured around the opening 15 and against the opposite faces of said wall 2, as clearly shown in Fig. 5.

Slidably mounted within the valve tube 12 is a valve stem 17 which is engaged through the guides 18 mounted in said stem 17 and has mounted on its inner end a valve 19 which is normally retained against the valve opening 13 by a coil spring 20 or the like engaged around said valve stem 17 and having one end secured thereto.

Secured to the bottom edge 7 of the upper helmet section is a lower helmet section including an inner wall 21 and an outer wall 22 which have their lower edges connected and are provided with a plurality of perforations 23 through which air exhaled by the party wearing the helmet may readily escape.

The upper section of the helmet is provided in its lower portion and at one side with a transversely extending sleeve 24 which has its outer end secured against the inner face of the outer wall 2, while its inner end is secured against the inner face of the inner wall 1 of said upper section. The inner end of the sleeve 24 is closed by a plate 25 which has a valve opening 26 therein against which is secured a slide valve 27 within the sleeve 24 and resting upon the valve rod 28 which is in turn pivoted intermediate its ends to the perforated transverse partition 29 positioned centrally in the sleeve 24 and through which the valve rod 28 extends. The outer end of the valve rod also projects through an opening 30 in the outer wall 2 and has a knob 31 mounted upon its outer extremity, by means of which said rod may be swung upwardly or downwardly upon its central pivot to move the slide valve 27 to position above or below the valve opening 26 and thereby allow a fresh supply of air from the sleeve 24 to enter the upper section of the helmet and travel around the person's head to the mouth and nostrils of said person at the front of the helmet.

It will be understood that the fresh air enters the sleeve 24 by way of the opening

32 in the upper portion thereof from between the inner wall 1 and outer wall 2 of the upper section of the helmet, and is prevented from escaping from the outer end of said sleeve 24, by means of a closure plate 70 33 mounted upon and movable with the valve rod 28 and positioned against the outer wall 2 to cover the opening 30 through which the valve rod 28 extends.

After the air fed to the interior of the helmet through the valve opening 26 has been inhaled and then exhaled by the party wearing the helmet, said air will, after it has been exhaled, pass out of the helmet by way of the openings 34 which are provided with a suitable flap valve 34' secured to the inner wall 21 of the lower section of the helmet which, it will be understood, is formed of rubber or other suitable flexible material, which will press tightly against the back of the party's head and the shoulders to prevent smoke and fumes from entering the bottom of said helmet and traveling upwardly therein. The exhaled air, after passing through the opening 34, will 80 travel downwardly in the lower section of the helmet and escape through the escape opening 23, previously mentioned.

The front of the lower section of the helmet is retained in proper spaced relation 95 with the party's face by means of the spacing cushion 35 secured to the inner face of the inner wall 21 of said lower section and having its inner edge resting in the groove between the lower lip and the chin, as 100 clearly shown in Fig. 2.

It will be readily seen that owing to the material from which the cross section of the helmet is formed, said lower section will at all times be securely engaged against the wearer and will automatically adjust itself to said wearer.

While I have shown and described the preferred embodiment of my invention, it will be understood that minor changes in 110 the details of construction, combination and arrangement of parts may be made without departing from the spirit and scope of the invention as claimed or sacrificing any of the advantages thereof.

What is claimed is:—

1. A device of the class described comprising a helmet, having an upper and lower section, said sections each formed of an inner and outer wall, a plurality of reinforcing plates positioned between the inner and outer walls of the upper section, an inlet valve projecting into the outer wall of said upper section, means carried by the upper section for controlling the passage of air from between the walls thereof to the interior of the helmet, said lower section secured to the upper section and formed of a flexible resilient material adapted to press against the shoulders of the wearer, means 120 125 130

for separating the lower section from the upper section, said lower section having its inner and outer walls connected at their lower edges and provided with air escape openings, said inner wall provided with openings, through which air exhaled by the party using the helmet escapes into the space between the walls, a flap valve arranged over said openings preventing air from being inhaled therethrough, and means in the upper section of said helmet for spacing the front of the helmet from the head positioned therein.

2. A device of the class described comprising a helmet including an upper section formed of inner and outer walls, means between said inner and outer walls for reinforcing the same, an inlet valve projecting into the outer wall of said upper section to control the entrance of air through the chamber formed by the inner and outer walls of said section, means mounted in the upper section for controlling the passage of air from between the walls thereof to the interior of the helmet, a lower section se-

cured to said upper section and formed of a flexible resilient material adapted to press against the shoulders of a person wearing said helmet, means for separating said lower section from the upper section, said lower section being formed with inner and outer walls having their lower edges connected and provided with air escape openings, said helmet being provided with openings in its inner walls through which air exhaled by the party using the helmet escapes into the space between the walls, a flap valve arranged over said openings preventing air from being inhaled therethrough, the lower section adapted to engage the back of the head positioned in said helmet, and means for spacing the front of the helmet from the head positioned therein.

In testimony whereof I affix my signature in presence of two witnesses.

CHARLES MATTHIEU EDELHAUSEN.
